UNITED STATES PATENT OFFICE.

THOMAS DANQUARD, OF NEW YORK, N. Y., ASSIGNOR TO AUTOPIANO COMPANY, OF NEW YORK, N. Y., A CORPORATION OF NEW YORK.

DOUBLE-SCALE PNEUMATIC MUSICAL INSTRUMENT.

No. 902,481.

Specification of Letters Patent.

Patented Oct. 21, 1908.

Application filed February 1, 1908. Serial No. 413,727.

To all whom it may concern:

Be it known that I, THOMAS DANQUARD, a citizen of the United States, residing at New York, in the county of New York and State of New York, have invented a new and useful Double-Scale Pneumatic Musical Instrument, of which the following is a specification.

This invention relates to that class of pneumatic musical instruments in which it is desired to use both the ordinary sixty-five note music sheets and also the full piano or eighty-eight note music sheets.

The principal objects of the invention are to provide for accomplishing this without moving the tracker or disturbing it in any way or manipulating the music rolls, and without providing for any covering of soft or flexible material of doubtful durability for one of the trackers while the other is in use as has been necessary in some classes of instruments designed for this purpose; also to provide a construction in which it is not necessary to use rubber or other flexible tubing.

Further objects and advantages of the invention will appear hereinafter.

Reference is to be had to the accompanying drawings, which show one form in which the invention may be embodied, and in which

Figure 1 is a front elevation of one end of the tracker-box showing how the invention may be applied thereto. Fig. 2 is a transverse sectional view of the tracker-box showing part of the action. Fig. 3 is a similar view of the slide valve and connections showing it in another position, and Fig. 4 is a rear elevation of the same.

In order to accomplish the above mentioned objects and otherwise simplify and improve this type of musical instrument the tracker-box 10, rolls 11 and 12, and action 13 are constructed in the usual manner, the action being provided with a full number; that is eighty-eight primary pneumatics 14. The tracker-bar is made in a plurality of parts or at least it is provided with a plurality of sets of note channels 15 and 16, each having an individual set of note conduits 17 and 18.

When the invention is designed for eighty-eight note and sixty-five note scales, the tracker or trackers will be provided with two series of channels, one for the eighty-

eight note music sheet, and the other for the sixty-five note music sheet. Assuming that there are eighty-eight channels 16 and conduits 18, these will be connected individually with the eighty-eight primary pneumatics 14 through a corresponding number of action conduits 20. It being kept in mind that it is necessary to provide for connecting all the conduits 18 with their respective conduits 20, and to change the connection so as to connect sixty-five of the conduits 20 with the corresponding conduits 17, at the same time disconnecting all the conduits 18 from the conduits 20, it will be seen that a very simple arrangement is provided for accomplishing this result. This consists, in the form shown, of a stationary block 21 fixed on the back of the tracker-box and having a flat surface 22 in which the several channels 17, 18 and 20 terminate, those of each series 75 being in one or more rows. A slide valve 23 is provided having a series of openings 24 always communicating with the conduits 20 in all positions of the valve, and having a second series of openings 25 adapted to communicate with the open ends of the conduits 17 and 18 in accordance with the position of the valve, and to close the other series or open it to the air as indicated in Figs. 2 and 3. This valve may be on either side of the block, but is shown on the rear, so that it may be readily accessible for repairs.

Bars 26 are mounted on the back of the block and springs 27 are located on the back of the slide and bear on these bars to hold the valve against the surface 22 and keep it to its seat. The slide valve is operated in any convenient way as by means of a shaft 30 having a series of arms 31 connected by links 32 with the slide valve and having another arm 33 which, with the arms 31, constitutes a lever. The opposite end of this is connected by an adjustable link 34 with one arm of a bell-crank 35 journaled in bearings in plates 36 supported by the tracker-box. The other arm of the bell-crank is connected with a slide 37 which passes through the end of the tracker-box and has a knob or handle 38 inside the tracker-box. The shaft 30 is journaled in bearings on the block 21. It will be seen that the position of the valve can be changed very readily by operating the knob or handle 38. The operation of the device will be clear from what has been stated, and it will be seen that the desired results can be 110

obtained by the use of a single tracker-bar with a plurality of sets of note channels, or by the use of a plurality of separate tracker-bars each fixed in stationary position, so that 5 they do not have to be manipulated or moved in any way.

While I have illustrated and described a preferred embodiment of the invention, I am aware that many modifications may be made 10 therein by any person skilled in the art without departing from the scope of the invention as expressed in the claims. Therefore, I do not wish to be limited to the details of construction shown, but

15 What I do claim is:—

1. In a pneumatic musical instrument, the combination of a tracker-box, a plurality of stationary trackers therein having a number of note channels, individual conduits connected with said channels, a block fixed on the rear of the tracker box and independent of the trackers and receiving said conduits, and a slide valve on the block for closing said conduits, and movable to a plurality of positions in each of which it connects the conduits of only one tracker with the conduits. 20

2. A pneumatic musical instrument comprising a plurality of sets of note conduits, and a movable valve for closing said conduits, said valve having a single series of passages adapted to be connected with the conduits of either set for opening them according to the position of the valve. 25

3. In a pneumatic musical instrument, the combination of a tracker box, a stationary block fixed to the rear thereof, a plurality of series of note conduits and a series of action conduits entering said block, a valve having means for controlling the connection of the 30 note conduits with the series of action conduits, and means for operating said valve having a handle or knob located within the tracker-box. 40

4. In a pneumatic musical instrument, the combination of a plurality of sets of note conduits, a block into which said note conduits enter, said block having a surface in which the conduits terminate, another set of conduits entering said block and terminating in 45 the same surface for connecting the first

named conduits with the action, and a valve movable along said surface for controlling the connection of the last set of conduits with any one of the sets of conduits. 50

5. In a pneumatic musical instrument, the combination of a tracker-box, a block fixed to the rear thereof, a plurality of sets of note conduits passing into said block, said block having a surface in which said note conduits terminate, channels leading to the action 55 from said block and terminating also in said surface, a slide valve having a series of openings always communicating with said conduits to the action in all positions of the valve, and having a series of passages communicating with said note conduits in different positions of the valve, and means for operating said valve. 60

6. In a pneumatic musical instrument, the combination of a tracker-box, a stationary block fixed on the rear thereof, a plurality of series of note conduits entering said block, a single series of action conduits entering said block, a slide valve for controlling the connection of the action conduits with the different series of note conduits, springs for holding said valve to its seat, and means for operating said valve comprising a slide extending through the end of the tracker-box and having a handle or knob located within 75 the tracker-box. 80

7. In a pneumatic musical instrument, the combination of a tracker-box, a block, a slide valve on said block for controlling the connection of the tracker with the action, a lever 85 on said block for reciprocating said slide, a link connected with said lever, a bell-crank near the end of the tracker-box, and connected with said link, and a slide extending from the other arm of the bell-crank into the 90 tracker-box, whereby said valve may be operated from the inside of the tracker-box. 95

In testimony whereof I have hereunto set my hand, in the presence of two subscribing witnesses.

THOMAS DANQUARD.
